UNITED STATES PATENT OFFICE.

WILLIAM SPARKS, OF JACKSON, MICHIGAN, ASSIGNOR TO SPARKS-WITHINGTON COMPANY, OF CLEVELAND, OHIO, A CORPORATION OF OHIO.

SIGNAL.

Application filed July 16, 1920, Serial No. 396,802. Renewed October 12, 1927.

This invention relates to certain improvements in signals. The primary object of the invention is the production of a signal of the motor driven or other type in which suitable adjustment is readily made, either to compensate for wear or to effect desired positioning of the diaphragm actuating member with reference to the diaphragm to produce such vibration of the latter as will result in the production of a satisfactory signal for the purpose at hand. Reference is hereby made to my co-pending application Serial No. 493,498 filed August 18, 1921, which application contains the broad claims to the subject matter here disclosed so far as it relates to the rear bearing for the motor shaft, the claims of this application being restricted to the particular construction of the rear bearing here shown and to the means for holding the shaft in contact with the rear bearing.

Another object is the production of a signal having the adjustment advantages above described in which the parts are normally so held in any position of adjustment as to prevent rattling of the same under ordinary conditions of use.

Other objects and advantages relate to the details of construction and arrangement by which the above set forth objects are attained, all as will more fully appear from the following description taken in connection with the accompanying drawings, in which:

Figure 1 is a rear end view of a motor driven signal with the motor enclosing case removed.

Figure 2 is a cross-section of the same.

Figure 3 is a front view of the same structure.

In general form the signal illustrated is much the same as that described in Letters Patent of the U. S. 1,237,717, issued upon my application under date of August 21, 1917, and reference is hereby made to my co-pending application, Serial No. 155,262, filed March 16, 1917, disclosing a related structure.

The signal as shown, comprises the usual diaphragm case section —1— through which the threaded ends —2— and —3— of a substantially U-shaped sheet metal motor case —4— extends for the reception of nuts —5— and —6— for rigidly connecting said parts.

The motor frame —4— carries the usual

pole pieces —7—, field coils —8— and commutator brushes —9—. The armature —10— of the motor is mounted upon the armature shaft —11— which has one end journaled in and extending through the rear wall —12— of the motor frame —4— and its opposite end journaled in and extending through the diaphragm case —1—, the latter end carrying forward of the said diaphragm case a toothed actuator, or cam —21— removably secured upon the shaft by means of nut —13—. The armature shaft carries a commutator —14— of any usual well known construction.

For the purpose of effecting adjustment of the armature shaft —11— and thereby the cam —21— toward the diaphragm —14— to properly position said cam with reference to wear-piece —15— there is provided a bar —16— adjustably secured to the wall —12— of the case —4— by means of screw —17—, said bar being normally tensioned away from the wall —12— and held in contact with the head of said screw —17— by means of spring —18— interposed between the said bar —16— and the rear wall —12— of the motor frame. One end of the bar —16— extends across the end of the motor shaft —11— so as to constitute an end thrust bearing for said shaft while the opposite end of the bar may rest in contact with or be secured to any stationary part of the device, and as shown, the end —19— of said bar is bent so as to extend at substantially right angles to the main portion of the bar, and rests in contact with the rear wall —12— of the motor frame, and preferably some means is provided for preventing lateral movement of said end portion —19— with relation to the motor frame —4—, and for this purpose the wall —12— may be provided with a recess or depression adapted for receiving the said end portion —19— to prevent any movement that would cause the end —20— of said bar to be moved out of alignment with the shaft —11—.

It will be readily seen that by adjusting screw —17— the end —20— of bar —16— will be moved either toward or from the wall —12— of the motor case to thereby move or permit movement of the shaft —11— to properly position cam —21— with reference to wear-piece —15—.

It is found that the construction so far described in like manner as the usual end

thrust bearing will prevent rearward movement of the shaft —11—, but has no effect upon its free forward movement toward wear-piece —15— with the result that under ordinary conditions of use upon motor vehicles, cam —21— will rattle and chatter against wear-piece —15—.

For the purpose of preventing such rattling and to hold the shaft —11— in position with its rear end in contact with bar —16— there is provided a spring member —22— as shown in the form of an elongated plate, having an intermediate bend, one end of which spring bar is mounted on the threaded end —2— of the motor case —4— at the rear of the nut —5—, the opposite end of the said bar contacting with the front end of the armature shaft —11—, the spring bar being so tensioned as to exert a thrust force upon the said shaft, tending to hold it in contact with the end —20— of bar —16—.

The operation and results of the construction will be readily understood by those skilled in the art, and the advantages obtained by such construction have been heretofore set forth.

Preferrably any desired adjustment of the structure desired can be effected without removing the motor case —23— shown in dotted lines in Figure 2, and for this purpose the said casing is provided with an opening adapted to register with and through which the end of said screw —17— may project or be accessible for adjustment purposes when the casing —23— is in assembled position.

The ends of the motor shaft —11— may perhaps preferably be of somewhat spherical form so as to have substantially point contact with the adjusting bar —16— and the spring tensioning bar —22—.

Although I have shown and described a specific construction as illustrative of a perhaps preferred form of the invention I do not desire to limit myself to the same, as many changes may be made in the details, of form, arrangement and construction of parts without departing from the spirit of this invention set forth in the appended claims.

What I claim is:

1. In a signaling device, a diaphragm, a diaphragm case section, a shaft extending through said case section, a cam member mounted on the forward portion of said shaft and between the diaphragm and said case section, and a spring member having an end portion rigidly confined with respect to said case section and its intermediate portion projecting away from said case section and its other end portion extending across the end of said shaft for resiliently holding the shaft from forward displacement.

2. In an acoustic signal, the combination of an elastic diaphragm, a support therefor, a cam for vibrating said diaphragm interposed between the diaphragm and its support, a rotary shaft on which said cam is mounted, and thrust bearings engaging both ends of said shaft, one of said bearings comprising a spring interposed between the diaphragm and the adjacent end of the shaft and adapted to yieldingly hold the shaft against the other thrust bearing.

3. In an acoustic signal, the combination of an elastic diaphragm, a support therefor, a cam for vibrating said diaphragm interposed between the diaphragm and its support, a rotary shaft on which said cam is mounted, and thrust bearings engaging both ends of said shaft, one of said bearings consisting of a leaf spring interposed between the diaphragm and the adjacent end of the shaft and adapted to yieldingly hold the shaft against the other thrust bearing.

4. A signaling instrument comprising an elastic diaphragm, a support therefor, a rotary shaft presented endwise toward the diaphragm, a bearing for the shaft, a cam mounted on the front end of the shaft between the bearing and the diaphragm and thrust bearings engaging both ends of the shaft, one of said bearings consisting of a spring interposed between the diaphragm and the adjacent end of the shaft and adapted to yieldingly hold the shaft against the other thrust bearing.

In witness whereof I have hereunto set my hand this 30th day of June, 1920.

WILLIAM SPARKS.
